UNITED STATES PATENT OFFICE.

AUGUST GOERTZ, OF NEWARK, NEW JERSEY.

DESIGN FOR A FRAME FOR PURSES OR BAGS.

SPECIFICATION forming part of Design No. 21,397, dated March 15, 1892.

Application filed June 2, 1890. Serial No. 354,057. Term of patent 7 years.

To all whom it may concern:

Be it known that I, AUGUST GOERTZ, a citizen of the United States, residing at Newark, in the county of Essex and State of New Jersey, have invented and produced a new and original Design for Purse or Bag Frames, of which the following is a specification, reference being had to the accompanying photographs, forming a part thereof.

10 This design is composed of two distinct elements to insure the beauty of the article. These consist, first, in the case or lid of a purse or bag or other similar frame, having a bas-relief representing the discovery of America by 15 Columbus, and, second, in arranging around the oval paneled top of the frame and encircling the bas-relief a wreath properly ornamented and provided with stars representing the States in the Union. The beauty and effect of this design are due to these features.

20 In the photographs herewith accompanying, Figure 1 shows my design in plan upon an oval paneled top or lid for a frame, and in Fig. 2 is represented a top view of a lid or 25 cover of a purse or bag provided with my new

and original design, which views are deemed sufficient to illustrate the leading features of the same.

Referring to said photographs of the design, Columbus is represented standing upon 30 his vessel, pointing to the newly-discovered land, while about him are grouped his men in various positions. Around this design is formed a wreath provided with stars. These are the essential features of my design. 35

What I claim, and desire to secure by Letters Patent, is—

The design for a purse or other like frame herein shown and described, consisting of an oval paneled top having thereon a bas-relief 40 representing the discovery of America, said panel being encircled by stars, as set forth.

In testimony that I claim the invention set forth above I have have hereunto set my hand this 31st day of May, 1890.

AUG. GOERTZ.
